UNITED STATES PATENT OFFICE.

FRANK KESSEL, OF MANSFIELD, OHIO, ASSIGNOR TO THE MANSFIELD LOCK WASHER COMPANY, OF MANSFIELD, OHIO, A CORPORATION.

LOCK-WASHER-MAKING MACHINE.

1,338,737.

Specification of Letters Patent.

Patented May 4, 1920.

Application filed December 18, 1916. Serial No. 137,701.

To all whom it may concern:

Be it known that I, FRANK KESSEL, a citizen of the United States, residing at Mansfield, in the county of Richland and State of Ohio, have invented certain new useful Improvements in Lock-Washer-Making Machines, of which the following is a specification.

The invention relates to machines for forming spring lock washers, of the type including a coil forming device, means for feeding a metallic rod or bar into the coil forming device, and means for severing the coiled bar at periodic intervals to form washers.

In machines of this general type, a reciprocating tool has been employed for squarely severing the completed washers, so that an intermittent feeding of the metallic bar has been required for permitting the return movement of the cutting tool in the periodic severing operation. This intermittent feeding operation not only necessitates complicated operating mechanism but also involves great wear and tear on the parts and consumes considerable time in the operation of the machine.

The principal object of the present improvement is to provide a continuously progressing cutter which will operate periodically to squarely sever the completed washers without interfering with a continuous feeding of the blank metallic stock or bar from which the washers are formed.

A further object of the improvement is to provide means for continuously feeding the metallic bar into the coil forming device at a uniform speed, and which may be thrown from an operative to an inoperative position and vice versa, without varying the relative fixed arrangement of the parts.

The objects of the invention thus generally stated, together with other and ancillary advantages, are attained by the construction and arrangement illustrated in the accompanying drawings forming part hereof, in which—

Figure 1 is a side elevation of the machine;

Fig. 2, a top plan view of the machine, a portion of the fly-wheel being broken away to show a detail of construction;

Fig. 3, a perspective view showing the manner of movably mounting one of the feed roller shafts;

Fig. 4, a front end view of the machine; 55

Fig. 5, an enlarged fragmentary side elevation of the severing mechanism;

Fig. 6, a fragmentary perspective view showing the coil forming means and a completed severed washer; 60

Fig. 7, a detail perspective view of the coil forming die; and

Fig. 8, a fragmentary detail view showing the bar coiled upon the end of the mandrel. 65

Similar numerals refer to similar parts throughout the drawings.

The machine includes the base or frame 1 having at one end a drive shaft 2 mounted to rotate in bearings 3 carried by the frame, 70 and having a drive pulley 4 at one end and an arm 5 at its other end, in the free end of which arm is adjustably mounted a cutting tool or blade 6; and at the other end of the frame a pair of driven shafts 7 and 7' are 75 rotatably mounted and provided with gear wheels keyed on one end and forming part of a train of gears 8 by which said shafts are geared to the drive shaft 2, and with feed rollers 9 and 9' keyed on the other ends 80 adapted to feed a metallic bar from which the washers are formed, through guide blocks 10 into a coil forming die 11 having a fixed mandrel 12 therein, said guiding and coiling means being suitably mounted 85 on the frame substantially midway between the drive shaft 2 and the driven shafts 7 and 7'; and the mandrel 12 being substantially parallel with said shafts.

The driven shaft 7 having the upper feed roller 9 fixed thereon is eccentrically journaled in a sleeve or bearing member 13 which in turn is journaled at its opposite ends in bearings 14 formed on the frame; and fixed on the sleeve 13 concentrically therewith is a collar 15 having a lever arm 16 formed integrally therewith.

The lower feed roller 9' is provided in its periphery with a groove 9^a of a depth slightly less than the thickness of the metallic bar and preferably of keystone shape; and on the free end of the lever a weight 17

is suspended for maintaining the feed rollers in operative position.

These parts are so proportioned and arranged that a downward rearward movement of the lever from an upright position will move the upper roller 9 toward the lower roller to impinge a bar entered between the rollers, to feed it into the coil forming device, the weight on the free end 5 of the lever being of a size to cause the rollers to exert a sufficient pressure upon the bar for properly feeding the same when in normal operative position. By this construction it will be evident that after the initial 10 adjustment of the parts, the upper feed roller may be swung into engagement with the bar inserted between the rollers without making any further adjustment of the parts, and when in such position will exert a uniform 15 pressure upon the bar to cause it to be properly fed into the coil forming device.

The guide blocks 10 are mounted one on top of the other and are adjustably secured in a cut-away portion or groove in the side 20 of the frame 1 as by means of bolts 18 and 18^a. The lower block is provided with a guide groove 19 which is bridged by the upper block to form a longitudinal guideway into which the bar enters upon leaving 25 the feed rollers and from which it is directed into the coiling means. The guide groove 19 is in a line radiating from the drive shaft 2, so that the cutting edge of the tool 6 travels squarely across the path 30 of the metallic bar as it is coiled upon the mandrel.

The coil-forming die is formed from a substantially rectangular fixed block which is secured to the frame in a cut-away portion 35 or groove, and slightly rearward of the guide blocks, as by means of a binding screw 20. Said block is provided in its forward end with a semi-circular recess in its outer face which forms a forming socket 21, and the inner wall of the recess is provided 40 with an opening 22 therein of slightly less diameter than the recess through which the outer end of the mandrel 12 is adapted to extend transversely thereof; and on the outer 45 face of the block at the upper forward end thereof a guide plate 23, having an outwardly and upwardly beveled face is secured as by means of a bolt 24.

The plate 23 serves to form between it and the inner wall of the recess a channel groove 50 which is aligned with the guideway in the guide blocks, so that after the metallic bar which is fed by the feed rollers passes through the guideway in the guide blocks, it is adapted to enter the upper portion of 55 the forming socket. As the bar is thrust into the socket it is coiled around the mandrel, and in the initial operation the forward end of the bar is manually bent laterally

outwardly as it approaches the deflecting 65 plate, so that in the further feeding movement of the bar, it engages with the beveled face of the plate, and thus a series of spiral coils are formed on the mandrel as shown in Figs. 6 and 8, as the bar is fed forwardly by 70 the rollers 9 and 9'.

As shown in Fig. 2, the mandrel 12 extends transversely through the frame and is adjustably secured therein as by means of a set screw 25. The outer end of the mandrel 75 is halved to form a cutting edge or anvil 12^a with which the cutting blade 6 on the free end of the cutter arm 5 is adapted to cooperate to squarely cut the bar and sever the completed washers. Preferably the mandrel protrudes a short distance outwardly from the die 11 so that at least one complete coil remains upon the mandrel after the severing operation, which renders unnecessary any further manual bending of the bar 80 to form the remaining spiral coils thereof.

The cutter arm 5, which is keyed on the outer end of the drive shaft 2, is preferably bifurcated at its free end for receiving the cutting tool or blade 6, and the bifurcated 90 portions are provided with longitudinal grooves in which the tool is secured by means of the clamping screws 26.

The free end of the cutting tool is inclined or retracted rearward from the cutting edge of the tool, so that the end of the tool not only immediately clears the severed end of the coil, but permits the same to be continuously advanced by the feeding mechanism without stopping, checking or reversing the same in the operation of the machine. After one severing operation, the cutting tool progresses continuously by rotation to the next severing operation.

The bar or rod from which the mandrel is 101 formed may be made longer than necessary, so that if the half round anvil on the outer end becomes broken in use, a new one may be formed thereon; and the die block is preferably provided with a forming socket 11 at each end, so that if one end becomes defective, the block may be reversed and its other end employed.

In the operation of the machine, the shafts 7 and 7' are driven by the shaft 2 11 through the train of gears 8 at a speed so proportioned to the speed of the driving shaft that the rollers 9 and 9' will feed the bar into the die just far enough to form a complete washer during each revolution of 12 the drive shaft. The cutter arm being fixed to the drive shaft will thus operate to sever a completed washer from the coiled bar at each revolution without interfering in any way with the uniform continuous feeding of 12 the bar 11.

I claim:

A machine for making lock washers and

the like, including a mandrel and a coil forming die, a rotary shaft in front of and substantially parallel with the mandrel, a guide-way and means in rear of the mandrel for feeding a bar forward to form a coil upon the mandrel, the guide-way being in a line radiating from the rotary shaft

and there being a shearing edge on the mandrel, and a cutting tool radiating from the rotary shaft having a shearing edge co-operating with the shearing edge of the mandrel for squarely cutting and severing washers formed on the mandrel.

FRANK KESSEL.
